(57) **CLAIM**

The ornamental design for a golf bag, as shown and described.

DESCRIPTION

FIG. 1 is a first perspective view of a golf bag; FIG. 2 is a second perspective view of the golf bag of FIG. 1;

FIG. 3 is a first side view of the golf bag of FIG. 1, shown in an alternate state;

FIG. 4 is a second side view of the golf bag of FIG. 3;

FIG. 5 is a front view of the golf bag of FIG. 3;

FIG. 6 is a rear view of the golf bag of FIG. 3;

FIG. 7 is a top view of the golf bag of FIG. 3; and,

FIG. 8 is a bottom view of the golf bag of FIG. 3.

The broken lines shown illustrate conventional stitching and form no part of the claimed design.
